Specification for Design.

Patented June 4, 1918.

Application filed June 13, 1917. Serial No. 174,632. Term of patent 14 years.

To all whom it may concern:

Be it known, that we, ELMER AINSLIE FORD, GERTRUDE L. PEW, and EDWARD J. KELLY, all and severally being citizens of the United States of America, and all residing in the borough of Manhattan, city, county, and State of New York, have invented a new, original, and ornamental Design for Book-Stops or Similar Articles, of which the following is a specification, reference being had to the accompanying drawings, forming part thereof.

In the drawing Figure #1 is a front elevation of a book stop illustrating our design and Fig. No. 2, a side elevation showing our new design.

We claim—

The design for a book-stop or similar article, as shown.

Dated, New York city, June 9, 1917.
